UNITED STATES PATENT OFFICE.

ALFRED STROMBERG AND ANDREW CARLSON, OF CHICAGO, ILLINOIS.

TELEPHONE-SWITCH.

SPECIFICATION forming part of Letters Patent No. 521,514, dated June 19, 1894.

Application filed January 26, 1894. Serial No. 498,135. (No model.)

To all whom it may concern:

Be it known that we, ALFRED STROMBERG and ANDREW CARLSON, citizens of the United States, residing at Chicago, in the county of Cook and State of Illinois, have invented a certain new and useful Improvement in Telephone-Switches, (Case No. 12,) of which the following is a full, clear, concise, and exact description, reference being had to the accompanying drawings, forming a part of this specification.

Our invention relates to telephone switches, and its object is to provide a switch conveniently located for use by the person using the telephone.

Our invention in its preferred form comprises a switch located upon the receiver, or hand telephone, in position conveniently to be closed by the hand of the person holding the telephone to his ear. The switch may serve to open and close the circuit through the subscriber's bell and generator, the primary circuit of his induction coil, or for any other desired purpose.

We will describe our invention more in detail in connection with the accompanying drawings, in which—

Figure 1 is a sectional view of a telephone receiver embodying our invention. Fig. 2 is a partial sectional view at right angles thereto. Fig. 3 is a sectional view on line 3—3, Fig. 2. Fig. 4 is a diagrammatic view illustrating the circuit connections when the switch is used for cutting the telephone out of circuit.

Like letters refer to like parts in the several figures.

Upon the interior of the casing *a* of the receiver is secured by one end a strip of metal *b* provided upon its free end with arms *b'* *b*². The arm *b'* normally rests against a contact *c*, being yieldingly held against the same by the spring *d* resting against the face of strip *b*. The spring *d* and strip *b* are secured in position by screws *e* *e*. Opposite the arm *b*² and normally out of contact therewith is provided a second contact *c'*, against which said arm *b*² may be caused to bear by the depression of button *f* which rests against the end of strip *b*. The depression of the button also serves to break the contact between the arm *b'* and contact *c*. Three binding posts *h* *h'* *h*² are shown upon the end of the receiver, one

of which, *h*, is electrically connected with the strip *b* which serves as the movable element of the switch, the other binding posts *h'* *h*² being connected respectively with the contacts *c* *c'*. As shown in Fig. 4 the telephone coil *k* may be included in circuit between contact *c'* and binding post *h*², while the contact *c* may be connected through binding post *h'* with the branch containing the bell *l* and generator *m*. The strip *b* normally rests against contact *c* so that circuit is closed through the circuit containing the bell and generator when the telephone is not in use.

When it is desired to use the telephone the button *f* is depressed by the thumb as the receiver is held in the hand, the circuit through the bell and generator circuit being thus opened, while circuit is closed through the telephone set.

The switch instead of being located at the transmitter end of the instrument may be placed in any other convenient location, but we preferably locate the switch at the transmitter end as the push button may thus be readily engaged by the thumb of the hand holding the telephone and depressed without conscious effort.

Instead of employing the switch for alternately including in circuit the calling apparatus and the telephone set, it is evident that the switch may be used for other purposes, as for instance, to open and close the primary circuit of the transmitter induction coil, our invention being capable of numerous adaptations. We do not, therefore, desire to limit ourselves to details of construction, but

We claim as new and desire to secure by Letters Patent—

1. The combination with a hand telephone, of a movable contact element provided thereon and adapted to be actuated by the hand holding the telephone, a telephone line, one side thereof terminating in said movable contact element, two contact anvils adapted to be alternately engaged by said movable contact element, signaling apparatus connected between one of said contact anvils and the second side of the telephone line, and a telephone set connected between the other of said contact anvils and the second side of the line; whereby either the signaling apparatus or the telephone set may be placed in circuit by the

manipulation of said contact element, substantially as described.

2. The combination with a telephone receiver provided upon its end with three binding posts, of a movable contact element carried thereon and connected with one of said binding posts, two contact anvils adapted to be alternately engaged by said contact element and connected respectively with the remaining binding posts, a telephone coil between one of said contact anvils and its binding post, a telephone line one side thereof being connected with the binding post con-

nected with said movable contact element, the other two binding posts being connected 15 by parallel branches with the opposite side of the line, and calling apparatus located in the branch that is not in circuit with the telephone coil, substantially as described.

In witness whereof we hereunto subscribe 20 our names this 24th day of January, A.D. 1894.

ALFRED STROMBERG.
ANDREW CARLSON.
